UNITED STATES PATENT OFFICE

RAYMOND L. JEWELL, OF MILLCREEK TOWNSHIP, ERIE COUNTY, PENNSYLVANIA, AS-
SIGNOR TO AMERICAN STERILIZER COMPANY, OF ERIE, PENNSYLVANIA, A COR-
PORATION OF PENNSYLVANIA

STERILIZER

Application filed October 27, 1928. Serial No. 315,567.

This invention is designed to facilitate the operation of a sterilizer. According to the present invention there is provided a steam supply, a sterilizer chamber, a filtered air inlet, an exhauster in the form of an ejector from the chamber, a valve mechanism by means of which steam may be turned into the chamber, a vacuum created in the chamber through the exhauster, and air admitted to the chamber after the creation of the vacuum through the filtered inlet, means being preferably provided to connect the chamber directly with the atmosphere controlling the manipulation of the contents of the chamber. Features and details of the invention will appear from the specification and claims.

A preferred embodiment of the invention is illustrated in the accompanying drawings as follows:—

Fig. 1 shows a central section of a portion of the chamber with the valve in place therein on the lines 1—1 in Figs. 2 and 3.

Fig. 2 is an elevation of the valve mechanism.

Fig. 3 a plan view of the valve disc.

Fig. 4 a section on the line 4—4 in Fig. 3.

Fig. 5 a section on the line 5—5 in Fig. 3.

Fig. 6 a section on the line 6—6 in Fig. 3.

1 marks the chamber wall, 2 the door frame, 3 a surrounding shell, and 4 a steam chamber surrounding the chamber wall, said steam chamber being connected with a source of steam supply (not shown) and forming a source of supply for the apparatus. A finish-

35 ing shell 5 is arranged outside of the shell 3. These parts are of common construction. A valve fitting 6 has a screw-threaded end 7 which is screwed into a threaded opening 8 in the door frame 2, the inner end of the fitting extending to within the wall 1 and the door frame extending between the wall 1 and shell 3.

40 A way 9 is arranged in the fitting and communicates with the chamber within the wall 1 and a way 10 is also arranged in the fitting and communicates with a passage 11 in the door frame, the passage 11 communicating with the chamber 4.

A seat member 12 is arranged above the fitting 6. It has a way 9a extending through it, the way 9a connecting with the way 9 and

a way 10a extending through it, the way 10a connecting with the way 10. A bonnet portion 13 is arranged above the seat member 12 and screws 14 extend through the bonnet member, the seat member and into the fitting 6, assembling the different parts of the valve body. An exhaust passage 15 leads from the seat member. It is in the form of a Venturi tube and operates as an ejector in connection with a nozzle 16 which is also connected in the seat member.

The upper face of the seat member forms a valve seat 17 and a port 18 extends from the valve face, or seat to the exhaust fitting 15. A port 19 extends from the nozzle 16 through the seat 17. The port 19 is connected by a radial port 20a in the valve 20 with the central supply passage 10a so that when the valve is properly turned steam is delivered through the nozzle and acts as an ejector.

45 A valve stem 21 is rotatably locked with the valve by means of pins 22 which extend through a flange at the lower end of the stem and into the valve. A spring 23 is tensioned between the upper face of the bonnet section and the flange and yieldingly holds the valve to its seat.

A handle 24 is secured on a hood 25 and the hood is mounted on the stem 21 and locked therewith by a key portion 26. The valve, therefore, may be readily rotated through the action of the handle.

50 A radial port 27 is arranged in the under face of the valve and is adapted to connect the ways 10a and 9a so as to turn a supply of steam from the chamber 4 into the sterilizing chamber within the wall 1, this positioning of the valve being indicated in Fig. 5.

A port 28 extends through the valve disc and is adapted to connect the way 9a with the space within the bonnet 13, thus permitting an exhaust of steam from the sterilizing chamber by way of the bonnet space and port 18 to the exhaust fitting.

This port 28 is connected with the way 9a and is consequently in position to exhaust the sterilizer chamber simultaneously with the positioning of the valve connecting the way 9a and consequently the chamber 4 with the nozzle 16 by way of the port 20a in the valve.

and the passage, or way 19 in the seat member, this positioning of the valve being shown in Fig. 1. A radial port 30 extends to a vertical port 31 in the under face of the valve and to a vertical port 32 extending through the top of the valve at the center. The port 31 is adapted to be brought into communication with the way 9a and the port 32 is connected with a passage 33 extending axially through the stem 21, the upper face of the valve being provided with a seat 35 into which the lower end of the stem is seated, thus making the connection. A filter chamber 36 is arranged in the upper end of the stem and is provided with a filter filling 37. The filter has a vent 38 in its upper cap providing an inlet from the atmosphere. This position of the valve bringing the port 31 in communication with the way 9a is illustrated in Fig. 4. The valve is also provided with a vertical port 39 which is adapted to be brought into communication with the way 9a and at this position all other ports are closed except the port 18. With the valve in this position the sterilizing chamber is in direct communication with the atmosphere. This position of the valve is illustrated in Fig. 6.

In the operation of the sterilizer, after the chamber is filled with material the valve is swung to the position shown in Fig. 1 delivering steam from the chamber 4 to the ejector thereby creating a partial vacuum in the sterilizing chamber. The valve is then turned to the position shown in Fig. 5 delivering steam from the chamber 4 to the sterilizing chamber. At the completion of the sterilizing action the valve is swung to the position shown in Fig. 6 connecting the sterilizing chamber with the exhaust. When the pressure in the sterilizing chamber has been exhausted the valve is again swung to the position shown in Fig. 1 creating a partial vacuum in the sterilizing chamber. The valve is then brought to the final position shown in Fig. 4 putting the sterilizer chamber in communication with the filtered air inlet, breaking the vacuum and permitting the door to be opened.

What I claim as new is:—

1. In a sterilizer, the combination of a sterilizer chamber; a steam supply connection; an air inlet filter; a valve body having ways connected to the chamber, a steam supply connection, inlet filter, and an exhaust to the atmosphere, said ways leading to a disc seat; an ejector operating on said exhaust; and a disc-shaped valve head ported with relation to the ways to connect the sterilizer chamber with the steam supply connection, the chamber and the exhaust with the steam supply connection connected with the nozzle, and the chamber with the filter.

2. In a sterilizer, the combination of a sterilizer chamber; a steam supply connection; a

valve body connected to the chamber and the valve supply connection, said body having a disc-shaped valve seat; ways in the body extending from the chamber through said seat; a way connected with the supply connection extending through said seat; a way corresponding to an ejector nozzle extending through said seat; a bonnet member forming a valve chamber from which an exhaust extends in relation to the ejector nozzle; a disc-shaped valve head rotatively mounted on the seat; and a filtered inlet connected with the valve head, said valve head being ported in relation to said ways and inlet to connect the chamber with the steam supply connection, the chamber with the bonnet chamber and exhaust, the steam supply connection with the ejector nozzle, and the filtered inlet with the chamber.

3. In a sterilizer, the combination of a sterilizer chamber; a steam supply connection; a valve body connected to the chamber and the valve supply connection, said body having a disc-shaped valve seat; ways in the body extending from the chamber through said seat; a way connected with the supply connection extending through said seat; a way corresponding to an ejector nozzle extending through said seat; a bonnet member forming a valve chamber from which an exhaust extends in relation to the ejector nozzle; a disc-shaped valve head rotatively mounted on the seat; and a filtered inlet connected with the valve head, said valve head being ported with relation to said ways and inlet to connect the chamber with the steam supply connection, the chamber with the bonnet chamber and exhaust, the steam supply connected with the ejector nozzle, the filtered inlet with the chamber, and the chamber with the exhaust.

4. In a sterilizer, the combination of a sterilizer chamber; a steam supply connection; an air inlet filter; a valve body having ways connected to the chamber, steam supply connection, and inlet filter; a valve head ported in relation to the ways to connect the sterilizer chamber and the steam supply connection and the sterilizer chamber and the filter; a valve stem for actuating the valve; a valve hood connected with the valve and extending over the valve; and a handle on the hood.

5. In a sterilizer, the combination of a sterilizer chamber; a steam supply connection; an air inlet filter; a valve body having ways connected to the chamber, steam supply connection and inlet filter; a valve head ported in relation to the ways to connect the sterilizer chamber and the steam supply connection and the sterilizer chamber and the filter; and a valve stem for actuating the valve, said stem forming a connection between the filter and the filter connecting way in the valve head.

6. In a sterilizer, the combination of a sterilizer chamber; a steam supply connec-

tion; an air inlet filter; a valve body having ways connected to the chamber, steam supply connection and air inlet filter; a valve head ported in relation to the ways to connect the sterilizer chamber and the steam supply connection and the sterilizer chamber and the filter; and a valve stem for actuating the valve, said stem forming a connection between the filter and the filter connecting way in the valve head, said stem also forming a mounting for the air filter.

In testimony whereof I have hereunto set my hand.

RAYMOND L. JEWELL.
